UNITED STATES PATENT OFFICE

ALONZO C. MATHER, OF CHICAGO, ILLINOIS

REFRIGERATOR CAR

Application filed December 11, 1929. Serial No. 413,329.

My invention relates to improvements in refrigerator cars, and it consists in the combinations, constructions, and arrangements herein described and claimed.

5 An object of my invention is to provide a refrigerator car in which a mechanical refrigerating system may be associated with the standard ice-cooling mechanism in a refrigerator car, and in which novel means is provided whereby the mechanical refrigerating system may be operatively connected with a portion of the car in such a manner that the moving car will actuate the system.

10 A further object is to provide a device of the type described in which a novel mechanical refrigerating system may be incorporated in a refrigerator car in such a manner that a minimum amount of space is displaced.

15 A further object is to provide a device of the type described whereby a mechanical refrigerating system may be employed for preserving the ice within the ice chambers in a refrigerator car, and while being normally actuated by the moving car the system is also provided with novel means whereby the system may be operated through an independent source of power.

20 A further object is to provide a device of the type described which, while providing means for preserving the ice within the ice chambers of a refrigerator car, may also be used for pre-cooling the car or may be used as a medium for maintaining a uniformly cool temperature within the refrigerator car

25 independently of the ice supply.

30 A further object is to provide a mechanical refrigerating system for a refrigerator car in which novel means is employed for mounting a major portion of the system underneath the car, and in such a manner as to eliminate interference with any of the standard constructions.

35 Other objects and advantages will appear in the following specification, and the novel features of the invention will be particularly pointed out in the appended claims.

40 My invention is illustrated in the accompanying drawings, forming part of this application, in which

45 Figure 1 is a side elevation of a portion of

a refrigerator car embodying my invention,

Figure 2 is a side elevation, partly in section, of one of the trucks associated with the car,

Figure 3 is a top plan view of the truck 55 and a portion of my invention,

Figure 4 is a sectional view taken along the line 4—4 of Figure 1,

Figure 5 is a diagrammatic view of the refrigerant circuit and the mechanism containing the same,

Figure 6 is an enlarged detail view of a portion of my invention, and

Figure 7 is a detail view of a portion of the structure shown in Figure 6.

55 In carrying out my invention I make use of a refrigerator car 1 which is mounted upon a pair of trucks 2. The car 1 and the trucks 2 preferably conform to standard constructions and, therefore, require no detailed description. The car is provided with a plurality of ice chambers 3 upon one end, and a similar plurality of ice chambers 4 is provided upon the opposite end, see Figures 1 and 4. The ice chambers may be filled with 70 ice through openings 5 in the top of the car, see Figure 4. The openings may be closed by means of covers 6. The ice chambers are preferably mounted upon a suitable rack construction 7, see Figure 1.

75 In referring to Figure 2 it will be noted that I make use of one of the trucks 2. The truck in part comprises a channel 8 which, in railroad parlance, is termed a sand plank. The sand plank supports a wooden block 9 upon which springs 10 are mounted. This mechanism is also old in the art. A platform 11, see Figure 2, is secured to the sand plank 8 by means of bolts or rivets 12. In referring to Figure 3 it will be noted that the platform 11 is substantially of a width equal to the distance between the wheels 13 associated with the truck. The platform may be bent as at 14 for providing a maximum amount of space in the locality of the brake beam 15.

80 The opposite end of the platform 11 is provided with openings through which depending members 16 project. The latter are provided with removable portions 17, see Figure 2, for permitting the members 16 to 100

be disposed upon an axle 18 which is associated with the wheels 13. A spring 19 is disposed upon each end of the members 16 and is held thereon by means of a nut 20 which may be adjusted for providing the proper tension in the spring.

A compressor 21 is mounted upon the platform 11 and is provided with a shaft 22 having a slideable gear 23 mounted thereon. This 10 gear is disposed in mesh with a gear 24 which is fixed upon the axle 18, see Figure 3. Referring again to Figure 3, I have shown a pair of condensers 25 and 26 as being mounted upon the platform. A pipe 27 connects 15 the compressor 21 with the condenser 25. The latter is connected with the condenser 26 through the medium of a pipe 28.

A pipe 29 leads from the condenser 26, see 20 Figure 4, and passes upwardly through the bottom of the car and is wound about one of the chambers 3 for providing a coil 30. The coil 30 is operatively connected with a coil 31 at 32, and the coil 31 is similarly connected with a coil 33 upon another of the ice chambers 3 as at 34. The coil 33 is in turn connected with a coil 35 upon the right hand ice chamber 3, in viewing Figure 4, at 36. The pipe 29 continues upwardly from the coil 35 and passes along the ceiling to the opposite 25 end of the car, and is wound in coil formation 30 about the individual tanks 4 and connected together in the same manner as are the coils 30.

A vapor pipe 38 connects the last coil 37 35 in the circuit with the compressor 21, see Figure 4. In Figures 3 and 4 I have shown a motor 39 as being mounted upon the platform 11. The motor is provided with a gear 40. The gear 23 is provided with a hub portion 41 operatively connected with a bar 42 40 whereby the gear may be shifted from the full line position to the dotted line position shown in Figure 6. The bar 42 is slidably mounted upon a bracket 42' by means of pins 45 43 which project through a slot 43' in the bar. One end of the bar projects through a slot 44 in the platform 11.

The gear 23 may be shifted into engagement with the gear 40 associated with the 50 motor 39 by moving the bar to the dotted line position shown in Figure 6. At this time the end 43'' of the bar is disposed within a recess 47 wherein the bar is rigidly held by reason of a spring 49. When the gear 23 is 55 disposed in mesh with the gear 24 as shown in Figure 3, the end of the bar 42 is disposed within a recess 45, see Figure 7. The gear 23 may be shifted to a neutral position at which time the gear is out of engagement with both 60 the gear 24 and the gear 40. At this time the end of the bar may be disposed within a recess 48. The recesses 45 and 48 are provided with spring members 46 and 50, respectively.

65 In operation, the ice chambers 3 and 4 are

provided with a supply of ice for cooling the interior of the refrigerator car. The mechanical refrigerating system is, of course, provided with the necessary amount of refrigerant. The gear 23 is then shifted into engagement with the gear 24. These gears are provided with relatively large teeth so that a slight vibration or movement of these two elements will not necessarily interfere with the efficient operation of the mechanism. It will thus be seen that when the refrigerator car is moved the compressor 21 will be operated. An important feature in connection with my invention is the fact that the ice within the ice chambers may be preserved for a relatively long time, and in the event that the car should for any reason stop for any length of time, the compressor may be actuated through the medium of the motor 39. A mere shifting of the gear 24 will operatively connect the motor with the compressor.

In addition to this, the mechanical refrigerating system will suffice for all practical purposes as a substitute for the ice. Furthermore, the refrigerator car may be precooled by means of the mechanical refrigerating system prior to the loading of the car and the filling of the ice chambers. A further important feature in connection with my invention is the fact that the platform 11 may be mounted upon a standard truck and provides means whereby a large portion of the mechanism may be used in connection with a standard refrigerator car, and without necessitating a rearrangement of any of the parts. Then again, the system is so arranged that the coils upon each end may be connected and operated as a unit through the medium of a single compressor.

Figure 5 shows a diagrammatic view of the installation. Vapor in the system passes to the compressor 21 through the pipe 38 and in the direction indicated by arrows 38'. The vapor is compressed and condensed when in the condensers 25 and 26. From these the liquid refrigerant is passed through the pipe 29 to the coils surrounding the ice chambers 3 and 4. In Figure 1 I have shown the pipes 29 and 38 as being provided with flexible joints 51.

I claim:

1. The combination of a car having a truck provided with a movable axle, a platform connected with the truck, a compressor and a condenser carried by said platform, a cooling unit disposed within said car and operatively connected with said compressor and said condenser, means for operatively connecting the compressor with said axle, a motor, shiftable means for operatively connecting the motor with the compressor and disconnecting the compressor and the axle, and depending members associated with said axle and arranged for partly supporting said platform.

2. The combination of a refrigerator car having an ice chamber provided with an open top portion and having a hatchway directly above said ice chamber whereby said ice chamber may be serviced with ice while the car is standing still, and a mechanical refrigerating system associated with said car and having a cooling coil surrounding said ice chamber, said mechanical refrigerating system being of such capacity as to remove just enough heat to maintain the ice in a frozen condition while the car is in motion.

3. The combination of a refrigerator car provided with a hatchway and having an ice chamber disposed directly beneath said hatchway, said ice chamber being provided with an open top portion whereby said chamber may be serviced with ice through said hatchway while the car is standing still, supporting means associated with said car, and a mechanical refrigerating system partly mounted upon said supporting means and arranged in operative relation with respect to the ice chamber for cooperating with the same and maintaining the temperature in the ice chamber at 32° Fahrenheit, said refrigerating system being provided for the purpose of removing sufficient heat to keep the ice from melting while the car is in motion.

4. The combination of a refrigerating car being provided with a plurality of wheels, hatchways at each end at the top of said car and having a plurality of ice chambers having open top portions disposed directly beneath said hatchways, and a refrigerating system provided with cooling coils associated with said ice chambers for removing sufficient heat to maintain the ice in said ice chambers in a frozen condition while the car is in motion, said refrigerating system having means whereby the power for operating said system is transmitted through the wheels of said car.

Signed at Buffalo in the county of Erie
and State of New York this 2d day of December, A. D. 1929.

ALONZO C. MATHER.
